United States Patent

Des. 239,233
Patented Mar. 23, 1976

239,233

DISPLAY RACK OR THE LIKE

William E. Taylor, Middleburg Heights, Ohio, assignor to
SCM Corporation, New York, N.Y.

Filed Aug. 26, 1974, Ser. No. 500,498

Term of patent 14 years

Int. Cl. D6—04; D20—02

U.S. Cl. D6—153

Fig. 1

Fig. 2

Fig. 3

Fig. 4

FIG. 1 is a front perspective view of a display rack or the like showing my new design;

FIG. 2 is a front elevation view thereof;

FIG. 3 is a side elevation view thereof; and

FIG. 4 is a sectional elevation view taken along 4—4 in FIG. 2.

I claim:

The ornamental design for a display rack or the like, as shown.
